IRONING TABLE

Anthony C. Koster, Chicago, Ill.

Application February 21, 1938, Serial No. 191,814

3 Claims. (Cl. 38—117)

This invention relates to ironing tables and more particularly to such of the folding type.

An important object of the invention is to provide a simple foldable supporting leg arrangement which is easily operated into opened and closed positions and in opened position affords ample rigidity and stability for the supported table top or board.

Another object of the invention is to provide separate front and rear leg assemblies which are independently movable to opened position but are cooperatively constructed and arranged whereby, upon movement of the rear leg assembly to closed position, the front leg assembly is engaged thereby and simultaneously moved therewith to closed position.

Other objects and advantages to be attained will hereinafter more fully appear in the following specification.

20 A structure embodying a practical adaptation of the invention is illustrated in the accompanying drawing:

Figure 1 is a perspective view showing the table with the supporting leg assemblies in opened position;

25 Figure 2 is a side view showing the leg assemblies in closed position; and

Figure 3 is an inverted plan view of the table with the leg assemblies in the closed position as shown in Figure 2.

Referring now to the drawing, the numeral 10 designates the table top or board which may be of the usual conventional shape. On the under-side of the top or board 10, near the rear end thereof, is a cleat 11 to which is attached a pair of bracket members 12 which are formed with looped bearing portions 13.

Hingedly mounted on the bracket members 12 is the rear leg unit 14 which is preferably formed integrally of a single metal rod bent to provide an intermediate transverse portion 15 which is journaled in the bearing portions 13 of the brackets 12 and from the opposite ends of which the pair of leg members 16 extend divergently. As shown, the leg members 16 are braced transversely by a cross member 17. Obviously, however, the unit may be additionally or otherwise suitably braced. In any case, however, it is preferable to provide the cross member 17, located substantially as shown, so as to engage and move the stay-rod of a front leg unit as hereinafter more fully described.

Hingedly attached to the leg members 16, as at 18, is a substantially V-shaped stay element 19, the looped end portion 20 of which is slidably sup-

ported on a longitudinal guide bar 21 secured at its opposite ends to the under-side of the table top or board 10, as at 22. The guide bar 21 is of such length and so located on the underside of the table top that sufficient movement is afforded the stay element 19 to permit the rear leg unit 14 to be folded compactly close to the under-side of the table top in closed position and also whereby the leg unit may be moved a considerable distance past dead center in its opened position and in which latter position the intermediate portion 20 of the stay element 19 engages the shouldered rear end portion of the guide bar 21 so as to firmly support the table top or board 10.

The front leg assembly comprises a triangular leg unit 23 which, as shown, may be formed of a single metal rod formed with the intermediate transverse portion 24 and convergent pair of leg extensions 25 which may be welded or otherwise suitably secured together at their meeting end portions 26. The intermediate transverse portion 24 of the front leg unit 23 is journaled in bearing brackets 27 on the under-side of the table top or board 10.

Hingedly attached, as at 28, to the end portion 26 of the front leg unit 23, is a stay rod 29 having a looped opposite end portion 30 slidably supported on a guiding and locking element 31 secured on the under-side of the table top or board 10 near the hinged support for the rear leg unit 14. This guiding and locking element 31, as shown, comprises a longitudinally disposed bar, the forward end portion of which is shouldered and attached to the under-side of the table top or board 10, as at 32, while the rear portion thereof is re-bent downwardly to provide an off-set loop 33 and the extreme end portion 34 being attached to the under-side of the table top or board 10.

In the opened position of the front leg unit 23, as shown in Figure 1, the looped portion 30 of the stay-rod 29 is engaged in said downwardly off-set loop 33 of the member 31, thereby releasably locking the leg unit in its opened position, and in conjunction with the opened rear leg unit 14, affording a substantially rigid support for the table top or board 10.

Obviously, the front leg unit 23 may be folded to closed position independently of the rear leg unit 14, if desired, by manually releasing the looped portion 30 of the stay-rod 29 from the retaining loop 33 of the guiding and locking element 31 and then moving said leg unit 23 to closed position. However, it is preferred to

provide the rear leg unit 14 with a tripping element 35 which is located and arranged so as to engage and move the looped portion 30 of the stay-bar 29 from the looped portion 33 of the element 31 just prior to engagement of said stay-bar 29 by the cross member 17 of the rear leg unit 14 when said rear leg unit 14 is moved to closed position. As shown, the tripping element 35 is rigidly attached to the intermediate transverse portion 15 of the rear leg unit 14 and is in the form of a tongue of proper form and length to engage the loop 30 of the rod 29 at one side of the retaining loop 33 of the element 31. After the loop 30 of the rod 29 is thus disengaged from the retaining loop of the guide element 31 the cross member 17 of the rear leg unit 14 engages said rod 29 and moves it forwardly, thereby causing the hingedly connected front leg unit 23 to swing upwardly on the bearing brackets 27 and at least nearly to its fully closed position.

While the foregoing is the preferred construction and arrangement for effecting the closing of the front leg unit by movement of the rear leg unit to closed position, it is obvious that either the cross member 17 of the rear leg unit or the tripping element 35 may be alone provided and utilized for the purpose.

From the foregoing description it is noted that while the front and rear leg units are separately constructed and mounted, they are so correlated that they cooperate to support the table top in opened position, and the peculiar form and mounting of the rear leg unit is an essential feature of the invention in that it provides the main support due to the lateral spread of the leg members 16 and the positioning of the unit past dead center, together with the engagement of the stay-member 19 with the shoulder at the end of the guide bar 21, and in cooperation with the support afforded by the front leg unit 23, as hereinbefore described.

It is to be understood that the structure admits a considerable modification within the spirit and scope of the invention as defined in the appended claims. The invention, therefore, is not limited to the specific construction and arrangement shown in the accompanying drawing.

What is claimed is:

50 1. A folding ironing table comprising a table top, a foldable rear leg unit hingedly mounted on the underside of the top adjacent the rear end thereof, means to limit rearward movement of

said rear leg unit to a predetermined position, a front leg unit hingedly mounted on the underside of the top forward of the rear leg unit, a stay-bar hingedly attached at one end to said front leg unit and having a looped opposite end portion, a guide bar located on the underside of the top between the front and rear leg units, said guide bar having a downwardly extending offset loop for the engagement of the looped portion of said stay-bar whereby to releasably hold said front leg unit in opened position, and a tripping element on said rear leg unit arranged and adapted to engage the looped portion of said stay-bar and release it from the offset loop of said guide bar when the rear leg unit is moved to closed position.

2. A folding ironing table comprising a table top, a foldable rear leg unit movable to a closed position under the top and to an opened predetermined supporting position past dead center, means to limit rearward movement of said rear leg unit to said predetermined position, a foldable front leg unit movable to a closed position under the table top, a stay element hingedly attached at one end to said front leg unit and having provision at its opposite end for slidably and releasable locking engagement with a guide element, a longitudinal guide element located on the underside of the top between said front and rear leg units, said guide element having a downwardly extending offset loop to receive the end portion of said stay element whereby to hold said front leg unit in opened position, and a tripping member on said rear leg unit to engage said stay element of the front leg unit and release it from the looped portion of said guide element when the rear leg unit is moved to closed position.

3. A folding ironing table comprising a table top, separate front and rear leg units hingedly attached to the underside of the top, means to limit rearward movement of the rear leg unit to a predetermined position, a stay element hingedly attached to the front leg unit and slidably guided longitudinally on the underside of the top, means for releasably locking the stay element of the front leg unit on its guiding means, and a tripping element on said rear leg unit to engage and release the stay element of the front leg unit from its locked engagement with the guiding means thereof when the rear leg unit is moved to closed position.

ANTHONY C. KOSTER.
